Patented Sept. 10, 1912.

UNITED STATES PATENT OFFICE.

CHARLES K. WOLF, OF NEAR XENIA, OHIO.

WIRE-WORKING APPLIANCE.

1,038,052.

Specification of Letters Patent. Patented Sept. 10, 1912.

Application filed May 23, 1910. Serial No. 562,845.

To all whom it may concern:

Be it known that I, CHARLES K. WOLF, a citizen of the United States, residing near Xenia, in the county of Greene and State 5 of Ohio, have invented certain new and useful Improvements in Wire-Working Appliances, of which the following is a specification.

My invention relates to wire working appliances, and particularly to wire stretching and splicing tools.

The object of the invention is to simplify the structure, as well as the means and mode of operation of such devices, whereby they 15 will not only be cheapened in construction but will be efficient in use, easily operated, and unlikely to get out of repair.

A further object is to provide such a tool which will be small and compact, adapted 20 to engage the wire in such way as to obviate any possibility of slipping, and to embody in one tool with the wire engaging means, wire straightening and wire twisting means.

With the above primary and other incidental objects in view as will more fully appear in the specification, the invention 25 consists of the features of construction, the parts and combinations thereof, and the mode of operation or their equivalents as 30 hereinafter described and set forth in the claims.

Referring to the drawings, Figure 1 is a perspective view of the tool, Fig. 2 is a perspective view showing the application of 35 the tool to the work. Fig. 3 is an end elevation of the implement. Fig. 4 is a perspective view, showing the application of the implement to the wire and the method 40 of engaging it therewith. Fig. 5 is a perspective view showing the wire and implement interengaged. Figs. 6 and 7 are perspective views showing the implement used 45 as a wire splicer or wire twister.

Like parts are indicated by similar characters of reference throughout the several views.

In constructing the device there is employed a bar *a* bifurcated at its extremity as at *b* and said slotted or bifurcated portion 50 is upturned or bent to U-form thereby forming two similar adjacently located hooks *c* separated by the slot *b*. The bar *a* preferably projects laterally beyond the hooks *c* forming shoulders *d* preferably inclined on 55 the upper or working surface. At the end of the bar *a* opposite the hooks *c* is a link

or ring *e*, in which to engage the pulling bar *f* which is fulcrumed on the post as shown in Fig. 3. The bar *a* may be provided with either one or two lateral shoulders *d* which 60 are used for twisting or splicing, or if the device is desired only for pulling or wire stretching purposes the shoulders may be omitted entirely.

Referring to Figs. 4 and 5 the wire *g* is 65 to be pulled in the direction indicated by the arrow. The implement is applied to the wire with the bar parallel thereto, the wire extending through the slot *b* and the device in a reverse position, or with the hook 70 end in the direction the wire is to be pulled. The implement is then reversed while maintained in engagement with the wire as shown in dotted lines in Fig. 4, the path of movement being indicated by darts. This 75 reversal of the implement causes the extremity of the wire to be bent to parallelism forming a bight or hook in the extremity of the wire about one of the hooks *c* of the implement as shown in Fig. 5. The slot *b* being but little 80 larger than the diameter of the wire will prevent the bent portion of the wire yielding or slipping when subjected to strain. A suitable pulling bar *f* is thrust through the link *e* and is fulcrumed on the post or in any 85 other convenient manner, to pull the wire to the desired tension. After the wire has been secured the implement, by reversing its previous movement, is employed to straighten the wire and remove the bight or bend 90 placed therein for pulling purposes. While in the drawing the device is shown as attached adjacent to the end of the wire, it is to be understood that it may be attached at any point throughout the length of the wire. 95

When used as a twisting device or for splicing, the implement is engaged with the wire with the main strand thereof passing through the hooks *c* as shown in Fig. 6. The splice wire or the strand to be wrapped about the main wire is engaged by the shoulder *d* as shown in said figure and the implement is turned about the main strand as about a pivot. The inclination of the shoulder *d* provides an extended bearing surface for the 105 splice wire, and causes the splice wire to be bent more gradually than if the shoulder is formed substantially square. It is to be understood however that the shoulder *d* may be made more or less abrupt or without the 110 inclination as shown in the drawings. If but one shoulder *d* is provided the device

will be equally serviceable, but the wrap of the splice wire can only be made in one direction, that is a right or a left hand wrap. By providing a shoulder on either side the 5 implement is made more convenient, in that it can be employed to wrap the splice wire in either direction.

From the above description it will be apparent that there is thus produced a device 10 of the character described possessing the particular features of advantage before enumerated as desirable, but which obviously is susceptible of modification in its form, proportion, detail construction, and arrangement of parts without departing from the principle involved or sacrificing any of its 15 advantages.

Having thus described my invention I claim;

20 1. As an article of manufacture, a wire stretching implement, comprising a bar having a slot extending inward from one end thereof, forming parallel fingers, the sides of said slot being substantially parallel 25 throughout, and separated by a space substantially equal to the diameter of the wire to be operated upon, the parallel fingers formed by said slot being bent upon themselves throughout an arc of substantially 30 one hundred and eighty degrees, having an intermediate space between the bar and fingers when so bent substantially equal to the diameter of the wire to be operated upon, the reversed portion of the fingers being ex- 35 tended somewhat beyond the strand of wire

when engaged therewith, substantially as specified.

2. As an article of manufacture, a wire working implement comprising a bar, the extremity of which is bent to parallelism 40 in U-shaped form, the arms of which are separated by a space substantially equal to the diameter of the wire to be operated upon, and an offset shoulder adjacent to the bend inclined in relation to the plane of the bar, whereby the extremity of the inclined shoulder will be below the plane of the bar and removed from the wire engaged in the U-shaped bend. 45

3. As an article of manufacture, a wire 50 working implement comprising a bar, parallel fingers projecting from the extremity of the bar bent upon themselves into U-shaped form and separated from each other by an intervening space substantially equal to the 55 diameter of the wire operated upon, a shoulder on said bar adjacent to the U-shaped fingers, said shoulder being inclined to the plane of the bar and substantially tangential to the exterior periphery of the U-shaped bend of said parallel fingers, and means carried by the opposite end of the bar to engage a pulling lever, substantially as specified. 60

In testimony whereof, I have hereunto set my hand this 20th day of May 1910.

CHARLES K. WOLF.
